CLAIM

The ornamental design for a handheld spiralizing device, as shown, and described.

DESCRIPTION

FIG. 1 is a perspective view of the handheld spiralizing device;

FIG. 2 is a side view of the handheld spiralizing device;

FIG. 3 is a side view of the handheld spiralizing device;

FIG. 4 is a top view of the handheld spiralizing device;

FIG. 5 is a bottom view of the handheld spiralizing device;

FIG. 6 is a perspective view of the handheld spiralizing device with an additional blade attachment;

FIG. 7 is a side view of the handheld spiralizing device with an additional blade attachment;

FIG. 8 is a side view of the handheld spiralizing device with an additional blade attachment;

FIG. 9 is a top view of the handheld spiralizing device with an additional blade attachment; and,

FIG. 10 is a bottom view of the handheld spiralizing device with an additional blade attachment.

The broken lines depicting the bottom of the blade mechanism are for illustrative purposes only and form no part of the claimed design.
